TYPE WHEEL ACTUATING MEANS IN SETTABLE PRINTING MACHINES

Jean Miossec and Rene Perret, Paris, France, assignors to Compagnie des Machines Bull (Societe Anonyme), Paris, France

Application June 9, 1953, Serial No. 360,462

Claims priority, application France June 18, 1952

5 Claims. (Cl. 101—91)

The present invention refers generally to a printing device comprising type wheels which are rotated by a motor driven mechanism by means of meshing gear wheels, and in which the type wheel, while in rotation is displaced in the plane of the wheel, in a manner which neutralizes the rotating movement of the wheel for a selected type thereon, the wheel being simultaneously displaced in a striking movement towards the paper, so that the selected type may be printed on the paper.

The invention especially concerns a device for aligning the types to be printed of the several type wheels, at the moment of the striking movement.

A machine to which the present invention could be applied is described in United States Patent No. 2,046,464, filed on March 30, 1933, and also in United States Patent No. 1,971,860 filed on March 10, 1933.

The use of printing devices of the above described character in tabulators controlled by perforated cards is well known. These machines comprise a great number of printing wheels which are able to print a large number of characters on the paper, at a relatively high speed.

A perfect alignment of these characters on the printed line is rather difficult to obtain, and requires great precision in the construction of the various parts which constitute a printing device.

Means for ensuring the alignment of the characters during the printing operation are well known in formerly used devices operating at a reduced speed but the application of these known means to devices built according to the aforementioned patents gives rise to difficulties because of the construction and of the very special way in which these devices operate.

An object of the present invention is to provide a printing device equipped with a number of type wheels which during the printing operation are continually in mesh, through suitable gearing, with a motor driven shaft, this machine being equipped with alignment devices which align the type wheels while said wheels execute the striking movement.

Another object of the invention is to provide a printing device, equipped with an aligning device for aligning a selected type to be printed of a type wheel, while said wheel is driven by the motor and while said wheel executes a complex movement, which results in the striking of said type on the paper.

Other characteristics of the present invention will appear in the description and in the appended drawings wherein:

Figs. 1 and 2, taken together and connected at the line X—X, are a vertical section of a printing device of the kind to which the present invention relates;

Fig. 3 is a fragmentary plan view of a record card for controlling the operation of the device in Figs. 1 and 2;

Fig. 4 is an explanatory diagram showing the relative displacements of different points on the elements of the printing device of Figs. 1 and 2;

Fig. 5 is an elevational view of an alignment device

2

for type-wheels embodying this invention, with part of the structure being shown in section and with elements of the printing device shown in broken lines;

Fig. 6 is an elevational view, partly in section, of a wheel alignment device constructed in accordance with another embodiment of this invention and shown in the position of rest thereof;

Fig. 7 is a view similar to Fig. 6, but showing the device in the operating position thereof for effecting alignment of a type-wheel during the striking movement of the latter; and

Fig. 8 is a diagram showing the timed relation between the movement of certain parts of the device in Figs. 1 and 2.

15 Since the structure and operation of the printing device to which the invention refers are well known from the above mentioned patents, it is merely necessary to give a summary of the description of this device.

The type wheel 21 (Fig. 1) is rotatable on an axle 22 which is fixed to a movable support 23, and is provided with gear teeth 24 on the periphery thereof driven constantly from a driving shaft 25, through the intermediary of gear wheels 26, 27 and 28 which turn freely on axles 30, 31, and 32 fixed on support 23. Wheel 28 20 moreover, constantly meshes with a gear wheel 33, which rotates freely on fixed shaft 34. Fixed to wheel 33 is a concentric ratchet wheel 35 (Fig. 2), provided with 10 teeth, one of which is suppressed. Next to ratchet 35, a sector 36 is swingably mounted on shaft 34 and has a slot 37, in which axle 38 of a catch 40 may slide. To catch 40 is linked a bar 41, as 40a, and the bar 41 may also pivot on an axle 42, fixed to part 43, which part in turn may pivot around the fixed axle 44. A bar 45 raised by the action of cams, not shown, brings back 30 part 43 to its rest position in which nose 46 is caught by nose 47 of lever 48, and in which position catch 40 is released from ratchet wheel 35, which is fixed with respect to gear wheel 33.

35 Lever 48, which may pivot around fixed axle 50, is kept in its initial position by means of spring 51, and is provided with arm 52 to which a rod 53 is attached, this rod being at its other extremity integral with an extension 53a of mobile armature 53b of a control electromagnet 53c which is energized at the desired moment by the current pulses coming from the control devices of the printing machine.

40 In the position shown in Fig. 2, part 43 is urged to pivot in a counterclockwise direction by spring 54, until nose 40b of catch 40 is engaged against ratchet 35.

45 Sector 36 is angularly urged in a counterclockwise direction around shaft 34, by means of a spring 56, which keeps arm 57 of the sector applied against bar 58. This bar 58 is also controlled by cams, not shown, and is moved once for each machine cycle, through a certain angle in the counterclockwise direction around shaft 34, thereby causing the teeth 60 of sector 36 to pass before nose 61 of lever 62. This lever 62 is pivoted on the fixed axle 44, and includes an arm 62a which is provided with nose 62b (Fig. 2) the outline of which mingles with the outline of nose 46 of lever 43. Lever 62 has an arm 62c to its left (Fig. 1), the extremity 62d is of arm 62c being situated above bar 63, and is drawn downward by spring 49. Bar 63 which is controlled by cams, not shown, brings lever 62 back to its rest position at the desired time (see diagram B—Fig. 8) in which position its nose 62b on its right hand end is caught by the nose 47 of lever 48, which also catches nose 46 of lever 43 in its rest position. In this position, nose 61 comes out of engagement with the teeth 60 of sector 36.

50 Support 23 carries on an axle 70, on which a roller 71 is rotatably mounted for rolling engagement with a part 72

integral with lever 72a. This lever which can pivot around a fixed axle 74 is acted upon by a spring 75 to engage a roller 73, mounted on lever 72a with a cam shaped shaft 76 (diagram A of Fig. 8).

To the left of support 23, Fig. 1, is a lever 77, which can pivot on fixed axle 78, and which under the action of spring 80 engages a roller 81 on lever 77 against edge 23a of support 23 to urge the latter to the right, as viewed in Fig. 1, so that roller 71 of this support is maintained in contact with part 72 of lever 72a. Support 85 of lever 77 is integral with the frame of the device, and is provided with grooves 86, in which part 23b of each support 23 may slide. Further, a stationary bar 87 is provided with grooves 87a, in which the lower extremity 23c of support 23 may slide. Each support 23 is provided with a first lug 88 which is disposed under the left hand extremity 43a of the lever 43, and with another lug 89, engaged in fork 90a of a lever 90 which is pivotally mounted on a fixed axle 91 carried by a stationary bar 91a, which is attached to the frame.

A bar 92 controlled by cams, not shown, returns support 23 to its lower rest position, by pressing against lever 90 at the desired time (diagram E—Fig. 8). Driving shaft 25 turns in a counterclockwise direction (Fig. 1), and has gear teeth thereon meshing with gear wheels 28 which in turn drives gear wheels 33 and 27. A gear wheel 26 meshes with gear wheel 27 and the gear teeth on type-wheel 21, the several wheels and the type-wheel being driven in the direction as indicated by the arrows on Fig. 1.

This device generally used in record card controlled machines, is in this case controlled by timed pulses emitted by a card analysing device.

The driving of shaft 25 (diagram F—Fig. 8) is such that type wheel 21 and ratchet 35 perform one revolution during a determined part of the machine cycle.

For an ordinary record card having 12 perforation locations in a column, as has the one shown in Fig. 3, the locations are usually numbered from 9 to 0 with 11 and 12, starting at the bottom of the card (line P—Fig. 8).

A letter may be indicated in each column by a combination of two perforations.

The Bull alphabetical code provides in each column (Fig. 3) a first perforation in one of the locations 9, 8, or 7, in combination with a second perforation in one of the locations from 6 to 12. When a card passes to the analysing station, which for several columns may include one row of analysing brushes, an impulse is emitted for each perforation analysed in a particular column and is sent to the control electromagnet (53c) of the corresponding printing device.

The movement of bar 58, Fig. 2 (diagram D—Fig. 8) is adjusted so that the teeth 69 of sector 36 pass in front of nose 61, in synchronism with the passage of perforation locations 9 to 7 of the card, at the analysis station. The analysis of one of these perforations energizes electromagnet 53c, which by its armature 53b—53a, exerts a pull on rod 53, thus causing lever 48 to pivot in a clockwise direction, and thereby free levers 62 and 43. The extremity 43a, which is held at its upper position by bar 45 (diagram C—Fig. 8), remains with its nose 62b in the engaged position, while lever 62, the bar 63 being at this moment lowered, pivots in a counterclockwise direction under the action of spring 49, so that nose 61 is engaged with a tooth of sector 36 which is stopped at a certain position, corresponding to the perforation analysed. If there has been no perforation in any of the locations 9 to 7, a perforation in one of the other locations of the column will cause the pivoting of lever 62 in the same way but this will be without any effect, since sector 36 is raised to its extreme upper position with nose 57 maintained against bar 58 by spring 56, bar 58 being itself stopped in its upper position. A pulse caused by the analysis of a perforation 6 to 0 or 11 or 12, causes lever

43 to pivot, and bar 45 being lowered after location 6 has passed the analysis station, no longer prevents such pivoting of the lever. When there is a pulse produced by a perforation at location 6, catch 40 engages with ratchet 35 while the latter is at rest.

Immediately after the passage of perforation location 6 of the card before the analysis station, driving shaft 25 begins to rotate, thereby causing the teeth of ratchet 35 to pass before the nose of catch 40, in synchronism with the passage of perforation locations 5 to 12 of the card in front of the analysis station.

The analysis of a perforation causes the emission of a pulse which energizes electromagnet 53c, controlling the pivoting of lever 52 and thereby the freeing of lever 43 which then pivots to permit the engagement of catch 40 with ratchet wheel 35. The rotation of ratchet 35 while the catch 40 is engaged therewith causes catch 40 to be displaced until stud 38 abuts against the extremity of slot 37 of sector 36 thereby to stop further rotation of the ratchet and gear wheel 33. The moment when catch 40 engages ratchet 35 and the previous positioning of sector 36, thereby determine during the machine cycle, the moment when the rotation of ratchet 35 and wheel 33 is stopped. It is to be noted that during the entire time during which the driving shaft 25 rotates, type wheel 21 rotates in a counterclockwise direction. From the moment when wheel 33 stops, the driving shaft 25 continues to rotate, and gear wheel 28 executes a rolling movement on gear wheel 33, while its axle 32 as well as movable support 23, in which the axle is fixed, move upwards.

The type wheel performs a rolling movement which is similar to the movement undergone by gear wheel 28, but in the opposite direction thus, it is a point located on the left hand side of the circumference of the type-wheel on a horizontal line passing through its axle 22, which is immobilized in the upper position.

By providing an additional movement of the type wheel towards the paper the type located at the point 40 of the wheel which is at this moment stationary, is printed on the paper carried by the platen F. Such additional movement is caused (Fig. 1) by part 72, which forms an extension of a lever 72a and is engaged by the roller 71 on support 23 to drive the latter to the left, or toward the 45 platen F, in response to upward movement of the support 23. When the printing is executed, roller 71 above the extension 72, and because of the action of spring 80 on lever 77 which is provided with roller 81 engaging support 23, the latter, and with it the type-wheel, are displaced towards the right. Stud 88 which is located at the lower part of support 23, raises the extremity 43a of lever 43 which pivots clockwise, thereby disengaging catch 40 from ratchet 35, and locking the nose 46 of lever 43 under the latch 47 on lever 48, electromagnet 53c no longer being energized. Wheel 33 being freed, said wheel and type wheel 21 may again rotate freely, under the action of driving shaft 25. When the last perforation location of the card has passed the analysing station, bar 92 is lowered and brings back lever 90 and therefore support 23 to its low position. This downward movement of support 23 accelerates the rotation of the type wheel. Cam shaft 76 which rotates continually is at this moment in a position in which the recessed portion 102 thereof is opposite the cam follower roller 73 so that spring 75 60 can pivot lever 72a including the part 72, toward the right to an extent sufficient to avoid contact of the roller 71 with the part 72 during the return of support 23 to its initial or lowered position.

Thus, for every tooth of ratchet 35 the ratchet may be stopped in any of four positions. Three of these positions are determined by the position in which sector 36 has been stopped by catch 61. The fourth position is determined by the sector 36 when stopped by the bar 58, 70 Since the rotation angle corresponding to the space

between two successive teeth of the teeth 60 on sector 36, is one quarter of the rotation angle between two teeth of the ratchet, ratchet 35 and gear wheel 33 may be stopped in 36 different positions, each of the last mentioned positions corresponding to a type and to a gear tooth of the type wheel 21. The rotation of gear wheel 28 and its vertical displacement (Fig. 4), when wheel 33 is blocked are such, that a point C on the pitch circle of gear wheel 28 moves along a part of an epicycloid said part being that one in which the epicycloid leaves and engages the pitch circle. For the part of the curve in question, this movement is infinitesimal, and is practically accomplished on a horizontal line. Assuming as is shown in Fig. 4, that the radius of all the gear wheels is R, and that the driving shaft 25 rotates through an angle α , and further discounting the effect of the lateral displacement of the upper end of support 23 during the upward movement of the latter. Wheel 33 being blocked by catch 40 engaged with a tooth of ratchet 35, a point *a* of wheel 28 rotates around stationary point C, and angle

$$\frac{\alpha}{2}$$

while travelling a distance $a-b$. The displacement $d-e$ of point *d* at the center of axle 32 is equal to half the displacement of point *a*, that is to say, axle 32 and support 23 which is attached to it are moved in an upward direction the distance

$$d-e = \frac{a-b}{2}$$

Point *f* is displaced by an angle

$$\frac{\alpha}{2}$$

and is also displaced a vertical distance equal to $d-e$ thereby bringing point *f* to point *g*. By this movement of wheel 28, wheel 27 performs a movement which is composed of two separate movements. Wheel 27 turns by an angle

$$\frac{\alpha}{2}$$

thereby causing point *m* to be moved downwards by distance $d-e$, while point *h* is moved upwards by the same distance $d-e$; at the same time, the support of axle 31 and wheel 27 are displaced upwardly by the distance $d-e$. The upward displacement of point *h* is therefore equal to twice $d-e$, and is therefore equal to $a-b$, while point *m* remains stationary, as does point C of wheel 28.

Wheel 26 performs the identical rolling movement around stationary point O, and type wheel 21 executes a rolling movement around stationary point P. Ratchet 35 which is integral with wheel 33 is blocked at a determined moment in such a way that point P of wheel 21 corresponds to the location of one of the types. In order to effect the striking movement of the type selected on wheel 21 towards platen F, a supplementary horizontal movement is imparted to the upper part of support 23 by part 72 which actuates roller 71 on support 23 in response to upward movement of the latter, so that point P of wheel 21 (Fig. 5) follows the dotted line p^1, p^2 in order to strike at point p^2 against the paper 151 which is carried by the platen F. The inking ribbon RE is located between all the type-wheels and the paper on the platen.

In order to ensure lateral alignment of the impressions printed by the various type wheels of the printing machine, an aligning device (Fig. 5) is provided for each type wheel, which device is adapted to cooperate with the roller 81 of Fig. 1, and is mounted on a support plate 150 (Fig. 5) which is fixed to the frame of the machine. To this plate 150, support 137 is fixed in an adjustable manner, by screw 220. The extremity of support 137

has notches 138, in which catch levers 152 for effecting the desired alignment are engaged. Each of these catch levers can pivot around an axle 153 fixed in a slot of support 137. For each type wheel, a related catch lever 152 is provided. Since this device is similar for each wheel, the device associated with one wheel only, is described.

The upper extremity of catch lever 152 forms a nose 154 which is adapted for engagement in the teeth of the related type wheel 21. The lower extremity of catch lever 152 is connected to one end of a spring 155, which is at its other end fixed to a rod 156, integral with support 137. Catch lever 152 also includes a notch 157 in which an extension of an axle 158 carrying a roller 159 is engaged, the roller 159 being loosely mounted on axle 158 which is integral with a lever 160; the operation of roller 159 is the same as that of the roller 81 in Fig. 1 in that, it is also engageable with the part 23b of the movable support 23. Lever 160 can pivot around an axle 161 which is fixed in support plate 150 which for each lever 160 has a notch 162 in which the related lever 160 is constantly engaged and guided. Under notch 157, catch 152 has an extension 139, which is adapted for striking against a stop 164 when the catch pivots to the right; this stop is adjustably mounted on support 137 by means of screw 165. The lower extremity of lever 160 is attached to one end of a spring 166 which at its other end is attached to a plate 167, fixed to plate 150, integral with the frame. The action of spring 166 prevails over that of spring 155. A sliding plate 168 is fixed in an adjustable manner by screw 170 to plate 150 integral with the frame of the machine, and it limits the clockwise pivoting of lever 160.

Notches 162 also form guides for part 23b of supports 23 of the type wheels. A spring plate 172 is fixed to support 137 by screws 173, and forms an extension 174 which is applied against each catch lever 152. The movements of the various points of type wheel 21 during the printing of a type are indicated in Fig. 5.

In Fig. 5, the gear wheels 28, 27 and 26 and the type-wheel 21 of Fig. 1 are shown. The reference 21a indicates the position of the wheel immediately after catch 40 (Fig. 1) has stopped wheel 33, at the point at which the upward movement of mobile support 23 begins.

When roller 71 of support 23 (Fig. 1) comes into contact with part 72, the upper part of mobile support 23 and type wheel 21 which it carries, are projected towards the left at the same time as the unit rises.

During this leftward movement, part 23b of mobile support 23 exerts pressure against roller 159 (Fig. 5). Lever 160 pivots towards the left, around axle 161, in response to the pressure against roller 159 and catch lever 152, drawn by spring 155 pivots towards the right, around axle 153 to engage nose 154 of catch lever 152 in the depression between two teeth of the type wheel thereby restraining movement of the type wheel with relation to point 153, however without impairing the striking action. For this purpose, nose 154 is kept engaged between the teeth of wheel 21 by spring 155 acting on lever 152 which follows the movement, pivoting around axle 153. During the striking action, the upper portion of mobile support 23 is projected to the left, and axle 158 of roller 159 leaves notch 157 of catch lever 152, when this catch lever is engaged between the teeth of wheel 21, but stop 164 is intended for limiting, if necessary, the amplitude of the movement of lever 160 and the clockwise rotation of catch lever 152.

In Fig. 5, are indicated approximately the relative movements of a certain number of points of the mechanism, starting from the moment when gear wheel 33 is blocked by engagement of catch 40 with ratchet 35, until the moment of the striking action on the paper. The movements illustrated in Fig. 5 complete the explanation of Fig. 4, in which the effect of part 72 on the sev-

eral movements has intentionally been left out, in explaining the rising movement of mobile support 23.

Axle 32 of gear wheel 28 rises from *d* to *e* because of the rolling movement of gear wheel 28 on wheel 33 which as is indicated in Fig. 4, is blocked, but on account of the leftward movement of the upper part of mobile support 23, axle 31 of gear wheel 27 actually passes from *s* to *t* (Fig. 5). Axle 30 of gear wheel 26 passes from *u* to *v*, and point *w* on the perimeter of wheel 26, instead of going from *W* to *W*₁ as has been indicated in Fig. 4, goes to *w*₂, under the combined action of the rotation movement of wheel 26 and of the leftward displacement of support 23. Axle 22 of type wheel 21 goes from *x*₁ to *x*₂, point *y* goes from *y*₁ to *y*₂, and point *z*₁ goes from *z*₁ to *z*₂.

Point *P* goes from *p*₁ to *p*₂, where the selected type is printed on the paper 151. The aligning of the characters printed by the types of the several type wheels is effected by the aligning catch levers 152, which in the example represented in Fig. 5 give a supplementary guidance to the related type wheels 21, when the following condition is realized. The arc of a circle *AC* concentric with the axle 153 and passing through the center of nose 154 of catch lever 152 intersects the pitch circle of the gear teeth of wheel 21 at point *A*₁ when the wheel 21 is at its starting position and during the striking movement of wheel 21, this point of the wheel goes to *A*₂ which is also on the arc *AC*; because of this, when nose 154 of catch lever 152 is engaged with the teeth of wheel 21, said catch lever follows the wheel in its displacement and imparts a certain restraining movement on the wheel in spite of the play and differences in the construction of the mechanism. Screw 220 which is used for fixing support 137, enables a precise positional adjusting of the pivoting axle 153 of catch lever 152.

During the striking movement, axle 22 of wheel 21, in passing from position *x*₁ to position *x*₂, Fig. 5, is displaced by an angle α_1 with respect to axle 32 of gear wheel 28; this displacement assuming that wheel 21 cannot rotate counterclockwise, as it is blocked by catch 152, amounts to a counterclockwise rotation of gear wheel 28, which taking its bearing on the gearing of shaft 25 turns wheel 33 a certain angle during the striking movement. This slight angular movement of gear wheel 33 frees catch 40 which is engaged in the toothed of ratchet 35, Fig. 1, and facilitates the disengagement of the catch from the ratchet.

Fig. 6 shows a modification wherein a part 205 which includes an aligning nose 210 and a press roller 206 is arranged so as to pivot around an axle 215, which axle is itself mounted on a lever 200 which oscillates around an axle 201. A spring 203 urges the lever 200 against the adjustable stop 202. Roller 206 is kept engaged in notch 211 which is cut in the left hand edge 23b of support 23, by a spring 207 which is hooked to eye 208 of part 205, and also to eye 209 of part 200.

During the blocking of wheel 33 (Fig. 1), support 23 is drawn upwards, and by this movement, roller 206 is ejected from notch 211 of edge 23b of support 23, therefore causing part 205 to pivot around axle 215. During this movement, nose 210 of part 205 advances towards type wheel 21, and is engaged (Fig. 7) between two teeth of said wheel. As the movement of the upper part of support 23 continues towards the left, lever 200 is carried along by said movement and therefore leaves stop 202.

When support 23 falls again, after the printing, lever 200 again comes into contact with stop 202, under the action of spring 203, then under the action of spring 207, nose 210 is disengaged from the teeth of type wheel 21, while roller 206 is kept by the same spring 207 in contact with edge 23b of support 23.

At the end of the downward movement of support 23, roller 206 again engages in notch 211 of part 23b in order to maintain the support in its low position (Fig. 6).

This mode of operation, which is simpler than the pre-

vious one also provides a more favorable equalization for the displacement of point *A*₁ towards *A*₂ represented in Fig. 5, pivoting point 201 (Fig. 6) being placed lower than point 153 (Fig. 5). The path followed by *A*₁ is closer to a horizontal line so that point *P* does not tend to rise again during the striking action.

The examples described are in no way restrictive, and are used only for the purpose of explaining how, according to the invention, a good alignment of types printed with type wheels may be obtained, these wheels performing a complex rolling and translation movement towards the printing position.

We claim:

1. In a printing machine especially adapted for connection with a record controlled tabulating machine; the combination of a stationary frame having a platen thereon, a movable type-wheel support in a position of rest opposite said platen, said support being adapted to move with a translatory motion with respect to said frame in a plane substantially at right angles to said platen, a type-wheel rotatably mounted on said support, said type-wheel having a plurality of types and gear teeth on the periphery thereof, a gear wheel rotatably mounted on said support, said gear wheel meshing with the gear teeth of said type-wheel and adapted to rotate in synchronism with said type-wheel, a continuously rotating shaft for rotating said type-wheel and thereby successively moving the types past a printing position, means operative to stop one point on the periphery of the gear wheel so that said gear wheel is compelled to roll along said one point and to impart, through the corresponding translatory motion of said support, both translational and rotational motion to the type-wheel so that said type-wheel performs a rolling movement in respect to said platen about a type in printing position, means to impart to said support and said type-wheel an additional movement towards the platen, a pivotable aligning lever between said platen and said type-wheel, means responsive to the additional movement of said support to pivot said aligning lever in a direction away from the platen to engage said aligning lever with said type-wheel during said rolling movement of said type-wheel, resilient means to permit said aligning lever, when engaged with said type-wheel, to pivot in the opposite direction to follow the movement of the type-wheel towards the platen to print the type in printing position, means to move said type-wheel and said support away from the platen after the printing of a type and means responsive to said last mentioned movement to pivot the aligning lever towards the platen away from the type-wheel into an initial position.
2. In a cyclically operated printing device the combination of a platen, a movable assembly in a position of rest opposite said platen, said assembly comprising a carrier, a toothed type-wheel rotatably mounted on said carrier and a gear transmission on said carrier, a continuously rotating driving shaft adjacent said assembly, said shaft rotating through said gear transmission to move in the types of said type-wheel successively past a printing position, selecting means operative to stop said type-wheel with a selected type in printing position and to effect movement of said assembly by said rotating shaft and said gear transmission out of the rest position of the assembly so that said type-wheel turns around said selected type in printing position, means responsive to the movement of said assembly out of its rest position to move said type-wheel with said type in printing position towards the platen to print said type, means operative to move said type-wheel and said carrier away from the platen after the printing of a type and type-wheel aligning means including a toothed portion disposed in an initial position between said platen and said assembly, said aligning means being responsive to the movement of said assembly out of its rest position to move said toothed portion in a direction away from the platen towards said assembly and into engagement with said type-wheel to thereby

align the type in printing position, said aligning means being further responsive to the movement of said assembly away from the platen after the printing of a type to return said toothed portion towards the platen to its initial position.

3. In a cyclically operated printing device the combination of a platen, a movable carrier in a position of rest opposite said platen, a toothed type-wheel rotatably mounted on said carrier, a continuously rotating driving shaft, a gear transmission between said driving shaft and said type-wheel, said driving shaft effecting rotation of said type-wheel to move the types of said type-wheel successively past a printing position, selecting means cooperating with said gear transmission to stop a type in printing position and to thereafter move said carrier out of its rest position in response to the continued rotation of said driving shaft so that the type-wheel turns about said stopped type, means responsive to said movement of said carrier out of its rest position to move said carrier with said type-wheel towards the platen, type-wheel aligning means including a toothed lever between said platen and said carrier, said toothed lever being pivotable about an axle maintained between said carrier and said platen in a substantial constant distance from said printing point, said aligning means being operated by said carrier when said carrier is moved out of its rest position, to engage said toothed lever with said type-wheel, at a circumferential point which approaches said axle during said movement of the carrier with the type-wheel towards the platen in order to align said type, by restraining the movement of said point of the rotating type-wheel with relation to said axle.

4. In a machine of the class described, the combination of a platen, analyzing means for analyzing record cards, a carrier in a position of rest opposite said platen, a toothed type-wheel rotatably mounted on said carrier, a gear drive including a continuously rotating shaft and a gear transmission for rotating said type-wheel to successively present the different types on said wheel at a printing position synchronously with the analyzing of a record card, positioning means controlled by said analyzing means in accordance with data on a record card to stop a corresponding type on said type-wheel in printing position and in cooperation with means included in said drive to move said carrier with the type-wheel out of its position of rest towards the platen, type-wheel aligning means including a toothed element in an initial position between said piston and said type-wheel, said aligning

means being operated by said carrier when said carrier is moved out of its position of rest to move said toothed element away from the platen towards said carrier and into engagement with said toothed type-wheel, said aligning means further including first resilient means to permit

5 said toothed element to move when engaged with said type-wheel in a direction towards the platen, means operative to move said type-wheel and said carrier away from the platen after the printing of a type, and second resilient means included in said aligning means and responsive to said movement of the carrier away from said platen to return said aligning lever to its initial position.

5. In a cyclically operated printing device a platen, a movable carrier in a position of rest opposite said platen, a toothed type-wheel rotatably mounted on said carrier, a continuously rotating driving shaft, a gear transmission between said shaft and type-wheel for rotating said type-wheel to successively move the types of said type-wheel past a printing position, means operative to stop a type 15 in printing position and to move said carrier and said type-wheel with said type in printing position towards the platen in response to continued rotation of said shaft, means operative to move said carrier and said type-wheel away from the platen after the printing of a type, aligning means including a type-wheel aligning lever pivotally mounted between said type-wheel and said platen and first and second resilient means, said aligning lever having a toothed portion adapted to engage said toothed type-wheel, said aligning means being actuated by said carrier 20 when said carrier is moved to pivot said aligning lever in one direction out of an inactive position into engagement with said type-wheel to align said type-wheel, said first resilient means being arranged to permit said lever thereafter to pivot in the opposite direction during the 25 movement of the carrier towards the platen, said second resilient means assuring the return of said lever to its inactive position when, after the printing operation said carrier is moved away from said platen.
